ELECTRICAL SHAVING MACHINE FOR DRY-SHAVING

Walter Brunner, Olten, Switzerland

Application March 27, 1933, Serial No. 663,035
In Switzerland March 31, 1932

8 Claims. (Cl. 30—12)

This invention relates to electrical shaving machines for dry-shaving including two serrated blades one of which is stationary and the other reciprocable. The object of the invention is to provide for eliminating the danger, inherent to the machines hitherto used, of individual hairs getting caught or pulled out, or the skin being injured, and rendering possible a safe and clean shaving.

10 This result is attained with the electrical machine for dry shaving, according to the present invention, by the provision of the stationary blade, which is in the form of an unhardened unground flexible lamel of a maximum thickness of 0.0028 inches and serrated on both longitudinal edges, being pressed together with an overlying flexible steel lamel of similar shape, but with smooth longitudinal edges and of somewhat greater thickness and slightly smaller width, so as to clear the teeth by means of a top plate held in position by screw bolts and concaved on its lower side in the transverse direction, against a carrier plate bridging the rigid hardened movable blade which is serrated on both longitudinal edges, so that the stationary blade and the steel lamel assume a flexed shape, in such manner, that on the one hand both of their longitudinal edges, projecting beyond the longitudinal sides of the top plate, form an angle exceeding 3° with the movable blade and on the other hand the flexible teeth of the stationary blade bear flat and resiliently, but firmly against the rigid teeth of the movable blade.

25 Advantageously, the carrier plate is adjustably secured to the body of the machine, this plate being for example fastened on threadedly connected supporting sleeves, so that by unscrewing the sleeves more or less the distance between the carrier plate and the movable blade and thus 30 the pressure between the teeth of the stationary blade and those of the movable blade can be adjusted.

The tips of the teeth of the blade snugly contacting with the skin are advantageously bent inwardly out of the plane of this blade, in order 45 to avoid injuring the skin by the tips of the teeth.

A constructional form of the invention is shown by way of example in the accompanying drawings, in which

40 Fig. 1 shows a side elevation of the shaving machine;

50 Fig. 2 is a front elevation of the machine, taken at right angles to Fig. 1 and showing a part section on the line II—II in Fig. 1;

55 Fig. 3 shows a larger scale section through the upper part of the machine on the line III—III in Fig. 2;

50 Fig. 4 is a section on the line IV—IV in Fig. 3, taken at right angles to the section shown in Fig. 3;

Fig. 5 shows a section on the line V—V in Fig. 3;

65 Fig. 6 shows in the left half a top view of the machine and in the right half a plan view thereof, with the blades, the carrier and connecting screws omitted;

Fig. 7 is a horizontal section on the line VIII—VIII in Fig. 3;

70 Fig. 8 shows a larger scale section transversely through the blades of the machine;

Fig. 9 is a partial top view of Fig. 8, and

Fig. 10 is a schematical view of the machine.

The tube 1 is screwed with its upper and lower end in a yoke 2 and a socket 3 respectively. To the socket 3 a sleeve 4 is threadedly connected 75 which forms with a terminal cap 5 screwed to its lower end a ventilator casing which at the same time serves as a handle. The terminal cap is provided with an inner upstanding hub providing a bearing and having a cylindric recess 80 6 for the reception of a felt packing in the form of an oil pad, for lubricating the bearing. A cap piece 7 screwed in the terminal cap 5 serves for closing the cylindric recess.

85 A slide housing 8 is mounted on the yoke 2 and subdivided into two superposed chambers by means of a partition wall, each of these chambers being in turn subdivided into two sections by thin steel slabs 9 inserted in slots 10 in the wall of the slide member. One of these sections of 90 each chamber contains a felt packing in the form of an oil pad, for lubricating the slides and eccentric means and the other section provides a guideway for slides 12 and 13 respectively. Each slide is formed with a guide track 19 comprising cylindrical walls and extending perpendicularly to the axis of the guideway and adapted for guiding slide blocks 14 and 15 respectively.

95 A shaft 16, which is mounted in the cap piece 7, the tube 1 and the slide housing 8, is connected at its lower end with a flexible shaft W (Fig. 10), by the aid of which it is actuated from an electromotor M.

100 The upper end of the shaft 16 is provided with two eccentrics 17 and 18 which are displaced relatively to each other through an angle of 180°. These eccentrics are mounted for rotation in the slide blocks 14 and 15 respectively, thus transforming the rotational movement of the shaft 16 into an oscillating movement of the slides 12 and 13.

105 A movable blade 20 is mounted on the upper slide 12, so as to bear against the same, and is provided at both of its ends with an aperture for receiving a projection 21 situated in the middle axis of the slide housing, so that the blade 20 is securely held in position on said slide. The movable blade consists of a rigid piece and is provided on both longitudinal edges with pointed 110 teeth. The slide 12 is guided in the guideway 115 120

by two steel platelets 23 which are slideable in grooves 24. The guideway of the slide 12 is closed at both ends by a cross member 26 which is secured in the slide housing by means of two head screws 27 passing also through the yoke 2 and a plate 28, thus holding these parts together.

In the cross members 26, guide sleeves 29 are provided in exact registry with the middle plane of the slide 12, the sleeves being shouldered at their upper ends and adapted to be screwed in the cross members more or less. These guide sleeves serve on the one hand as safety guide means for the movable blade 20 and on the other hand as supports for a carrier plate 30 which bears against the shoulders on the guide sleeves and forms a bridge across the movable blade.

Furthermore, on the guide sleeves 27 a stationary blade 31 is slid as well as a steel lamel 32 and a vaulted top plate 33. The stationary blade 31 is made of flexible material in the form of a piece of sheet steel of a uniform thickness of less than 0.0028 inches. This blade is serrated on both longitudinal edges and of a width which is larger than that of the movable blade 20 substantially for the length of their teeth. The flanks of the teeth are formed by outwardly curved portions and the width of the tooth gaps amounts to maximum 0.0108 inches at the narrowest part i. e. at the root. The tips 34 of the teeth of the stationary blade 1 are bent off at right angles in the downward direction, so as to prevent the sharp tips from contacting with the skin. The top plate 33 is pressed on the carrier plate 30 by means of two head screws 35 the heads of which are of rectangular shape, looking in the axial direction of the screw, and are guided in corresponding recesses in the top plate. The carrier plate in turn presses the steel lamel 32 on the stationary blade 31, so that the longitudinal edges or margins of these parts are resiliently urged against the movable blade 20. The screws 35 are screwed with their ends in nuts 36 which bear against the lower side of the plate 28 and which are guided with cylindric shafts 36a (Fig. 3) in clamping sleeves 37, whereby an undesired loosening of the nuts is prevented.

The stationary blade and the steel lamel are bent to assume the desired curvature by the pressure exerted by the head screws 35, suchwise, that on the one hand their longitudinal edges projecting laterally beyond the top plate form with the movable blade 20 an angle α which exceeds 3° and on the other hand the flexible teeth of the stationary blade come to bear flat but resiliently on the rigid teeth of the movable blade.

Laterally on the machine two rake-shaped guards 38 are arranged which are connected to the yoke 2 by head screws 39. The tines of the guard are provided with exterior extensions 38a which reach up to the level of the stationary blade so that the severed hairs are blown outwardly through the slots between the tines of the guard sliding over the skin, in the direction of the arrows in Figs. 4 and 5. Thus, on both sides of the machine a nozzle 40 of oblong cross section is formed by the guards in conjunction with the side walls of the slide housing 8, the nozzle opening directly on the teeth of the two blades and communicating on the other hand with an annular chamber in a tubular member 41 which is inserted in the socket 3. In the hollow space of the sleeve 4 forming the handle, a stage ventilator is accommodated the guide wheels 42 of which are held in position by a ring 43 inserted in the sleeve

and the impellers 44 of which are slid on the shaft 16 with their hubs and secured on the same by keys 46. The stage ventilator draws in air through apertures 5a of the cap 5 to press the air through holes 3a in the socket 3 and through the tubular member 41 towards the nozzles 40, so that a continuous stream of air for blowing off the severed hairs is provided for during the shaving.

When the machine is operative, the impact of the movable masses of the slide 12 for actuating the movable blade is compensated by the counter action of the slide 13, the apparatus thus being free from vibrations.

The slide housing is covered at the top by a thin guard plate 25 the rectangularly depending margins of which extend into grooves in the side walls of the slide housing, cuttings of hair being thus prevented from entering the interior of the guideway.

In each end portion of the upper slide 12 a U-shaped wire spring 22 is accommodated, for cushioning the impacts that are apt to be transmitted by the movable blade on the projections 21, due to a small amount of intervening play.

When the shaft 16 is set in rotation by the motor M, the two slides 12 and 13 reciprocate in opposite directions, the upper slide 12 actuating the movable blade 20 so as to perform a quick reciprocating movement, the hairs of the beard being thus cut between the teeth of the movable and the stationary blades. Due to the spring inherent to the stationary blade the teeth of this blade are adapted to adjust themselves separately, so that play between opposite teeth is avoided which may cause individual hairs to get clamped or be pulled out. At the same time the teeth of the stationary blade are continually sharpened by those of the movable blade. The length along which the teeth bear against each other is adjustable by means of the two guide sleeves 29. The pressure exerted by the top plate 33 for flexing the stationary blade 31 together with the steel lamel 32 is counteracted by the carrier plate 30, thus preventing undue friction arising between the two blades and consequent heating up of the blades. This pressure results in effecting frictional engagement between those teeth that are swept by the stream of cooling air. The stationary blade 31 is in its flexed condition wider than the movable blade, so that the latter is adapted to cut the coarse hairs for example of a bristly beard at the inner narrow part a (Figs. 8 and 9) of the tooth gaps of the stationary blade. The exterior wider part b of the tooth gaps of the stationary blade serves for introducing the individual hairs in the tooth gaps and directing them to the inner part a thereof, where the cutting operation sets in.

In this manner it is possible to cut hairs that are growing in an inclined disposition to the surface of the skin in erected position, thus at right angles to their shafts. On the other hand the small knob formed around the lower end of the shaft of each hair by the cuticula is forced back by the teeth of the stationary blade, without contacting of the skin bulging upwardly between the hairs into the inner narrow part of the tooth gap of the stationary blade, due to the pressure exertion of the teeth, with the movable blade is possible. Thus, the hair is cut off flush with the surface of the skin without endangering the skin. Furthermore no pustules that may be present on the skin can enter in

that very narrow part of the tooth gap and thus be cut off.

Due to the fact that several teeth on the movable blade pass over each tooth gap in the stationary blade in a rapid succession, the hair held in the tooth gap is severed by the conjoint action of a plurality of teeth. The number of cuts thus effected by the individual teeth is inversely proportional to the speed at which the machine is passed over the surface to be shaved. It is obvious that this speed can be varied at will. As the tines of both guards are outwardly prolonged, both air passages remain connected with the open through the slots in the guards during the shaving. By this means the hair cuttings are continually blown off, the compressed air supplied by the ventilator impinging on the serrated edges rubbing against each other in dry condition along the full length of these edges, whereby the latter are cooled and the hair cuttings are removed by being blown through the slots in the guard.

With a view to illuminating the surface to be shaved, the electromotor is adapted for feeding also a small incandescent lamp.

In order to permit balancing the two slides 12 and 13 relatively to each other, the lower slide 13 may be provided with a counterweight 47.

I do not limit myself to the particular size, shape, number or arrangement of parts as shown and described, all of which may be varied without going beyond the scope of my invention as shown, described and claimed.

What I claim is:

- 35 1. In an electric shaving machine for dry shaving, in combination, a stationary cutting blade in the form of an unhardened unground flexible lamel of a maximum thickness of 0.0028 inches, serrated longitudinal edges on said stationary cutting blade, a flexible steel lamel of similar shape as said stationary cutting blade, but with smooth longitudinal edges and of somewhat greater thickness and slightly smaller width so as to clear said teeth on said stationary blade, superimposed on said stationary cutting blade, a rigid hardened movable cutting blade situated underneath said stationary cutting blade, serrated longitudinal edges on said movable cutting blade, a carrier plate centrally arranged between said stationary and said movable cutting blade and extending longitudinally of said blades, a top plate of smaller width than said lamel and concaved in the transverse direction overlying said lamel, screw downs for said top plate for flexing said lamel and said stationary cutting blade with the aid of said carrier plate down on said movable cutting blade for pressing the flexible teeth of said stationary cutting blades against the rigid teeth of said movable cutting blade, and means for actuating said movable cutting blade in the flexed condition of said stationary cutting blade.
- 45 2. In an electric shaving machine for dry shaving, in combination, a stationary cutting blade in the form of an unhardened unground flexible lamel of a maximum thickness of 0.0028 inches, serrated longitudinal edges on said stationary cutting blade, a flexible steel lamel of similar shape as said stationary cutting blade, but with smooth longitudinal edges and of somewhat greater thickness and slightly smaller width so as to clear said teeth on said stationary blade, superimposed on said stationary cutting blade, a rigid hardened movable cutting blade situated underneath said stationary cutting blade and of a width which is smaller than that of said stationary cutting blade substantially by the length of the teeth of the latter, serrated longitudinal edges on said movable cutting blade, the teeth of said movable cutting blade only covering the inner ends of the tooth gaps of said stationary cutting blade, a carrier plate centrally arranged between said stationary and said movable cutting blade and extending longitudinally of said blades, a top plate of smaller width than said lamel and concaved in the transverse direction overlying said lamel, screw downs for said top plate for flexing said lamel and said stationary cutting blade with the aid of said carrier plate down on said movable cutting blade for pressing the flexible teeth of said stationary cutting blade against the rigid teeth of said movable cutting blade, and means for actuating said movable cutting blade.
- 55 3. In an electric shaving machine for dry shaving, in combination, a stationary cutting blade in the form of an unhardened unground flexible lamel of a maximum thickness of 0.0028 inches, serrated longitudinal edges on said stationary cutting blade, a carrier plate centrally arranged between said stationary and said movable cutting blade and extending longitudinally of said blades, a top plate of smaller width than said lamel and concaved in the transverse direction overlying said lamel, screw downs for said top plate for flexing said lamel and said stationary cutting blade with the aid of said carrier plate down on said movable cutting blade for pressing the flexible teeth of said stationary cutting blades against the rigid teeth of said movable cutting blade, and means for actuating said movable cutting blade in the flexed condition of said stationary cutting blade.
- 60 4. In an electric shaving machine for dry shaving, in combination, a stationary cutting blade in the form of an unhardened unground flexible lamel of a maximum thickness of 0.0028 inches, serrated longitudinal edges on said stationary cutting blade, a flexible steel lamel of similar shape as said stationary cutting blade, but with smooth longitudinal edges and of somewhat greater thickness and slightly smaller width so as to clear said teeth on said stationary blade, superimposed on said stationary cutting blade, a rigid hardened movable cutting blade situated underneath said stationary cutting blade and of a width which is smaller than that of said stationary cutting blade substantially by the length of the teeth of the latter, serrated longitudinal edges on said movable cutting blade, the teeth of said movable cutting blade only covering the inner ends of the tooth gaps of said stationary cutting blade, a carrier plate centrally arranged between said stationary and said movable cutting blade and extending longitudinally of said blades, a top plate of smaller width than said lamel and concaved in the transverse direction overlying said lamel, screw downs for said top plate for flexing said lamel and said stationary cutting blade with the aid of said carrier plate down on said movable cutting blade for pressing the flexible teeth of said stationary cutting blade against the rigid teeth of said movable cutting blade, and means for actuating said movable cutting blade in the flexed condition of said stationary cutting blade.
- 65 5. In an electric shaving machine for dry shaving, in combination, a stationary cutting blade in the form of an unhardened unground flexible lamel of a maximum thickness of 0.0028 inches, serrated longitudinal edges on said stationary cutting blade, a flexible steel lamel of similar shape as said stationary cutting blade, but with smooth longitudinal edges and of somewhat greater thickness and slightly smaller width so as to clear said teeth on said stationary blade, superimposed on said stationary cutting blade, a rigid hardened movable cutting blade situated underneath said stationary cutting blade, serrated longitudinal edges on said movable cutting blade, a carrier plate centrally arranged between said stationary and said movable cutting blade and extending longitudinally of said blades, a top plate of smaller width than said lamel and concaved in the transverse direction overlying said lamel, screw downs for said top plate for flexing said lamel and said stationary cutting blade with the aid of said carrier plate down on said movable cutting blade for pressing the flexible teeth of said stationary cutting blade against the rigid teeth of said movable cutting blade, and means for actuating said movable cutting blade in the flexed condition of said stationary cutting blade.
- 70 6. In an electric shaving machine for dry shaving, in combination, a stationary cutting blade in the form of an unhardened unground flexible lamel of a maximum thickness of 0.0028 inches, serrated longitudinal edges on said stationary cutting blade, a carrier plate centrally arranged between said stationary and said movable cutting blade and extending longitudinally of said blades, a top plate of smaller width than said lamel and concaved in the transverse direction overlying said lamel, screw downs for said top plate for flexing said lamel and said stationary cutting blade with the aid of said carrier plate down on said movable cutting blade for pressing the flexible teeth of said stationary cutting blade against the rigid teeth of said movable cutting blade, and means for actuating said movable cutting blade in the flexed condition of said stationary cutting blade.
- 75 7. In an electric shaving machine for dry shaving, in combination, a stationary cutting blade in the form of an unhardened unground flexible lamel of a maximum thickness of 0.0028 inches, serrated longitudinal edges on said stationary cutting blade, a rigid hardened movable cutting blade situated underneath said stationary cutting blade, serrated longitudinal edges on said movable cutting blade, a carrier plate centrally arranged between said stationary and said movable cutting blade and extending longitudinally of said blades, a top plate of smaller width than said lamel and concaved in the transverse direction overlying said lamel, screw downs for said top plate for flexing said lamel and said stationary cutting blade with the aid of said carrier plate down on said movable cutting blade for pressing the flexible teeth of said stationary cutting blade against the rigid teeth of said movable cutting blade, and means for actuating said movable cutting blade in the flexed condition of said stationary cutting blade.

ting blade in the flexed condition of said stationary cutting blade.

5. In an electric shaving machine for dry shaving, in combination, a stationary cutting blade in the form of an unhardened unground flexible lamel of a maximum thickness of 0.0028 inches, serrated longitudinal edges on said stationary cutting blade, outwardly curved portions of the teeth of said serrated edges extending into the intervening tooth gaps to provide a larger exterior width for said gaps and narrow inner ends of the gaps, a flexible steel lamel of similar shape as said stationary cutting blade, but with smooth longitudinal edges and of somewhat greater thickness and slightly smaller width so as to clear said teeth on said stationary blade, superimposed on said stationary cutting blade, a rigid hardened movable cutting blade situated underneath said stationary cutting blade, serrated longitudinal edges on said movable cutting blade, a carrier plate centrally arranged between said stationary and said movable cutting blade, and extending longitudinally of said blades, a top plate of smaller width than said lamel and concaved in the transverse direction overlying said lamel, screw downs for said top plate passed through said supporting sleeves for flexing said lamel and said stationary cutting blade with the aid of said carrier plate down on said movable cutting blade, rectangular heads of said screw downs fitted into corresponding recesses in said top plate for preventing rotational displacement of the screw shafts, nuts provided on the shafts of said screw downs, an enlargement of said nuts locked to the machine body a screw threaded sleeve connected to said enlargement, a clamping sleeve arranged in the machine body for engaging said sleeve for securing the same on the screw shaft, and means for actuating said movable cutting blade in the flexed condition of said stationary cutting blade.

6. In an electric shaving machine for dry shaving, in combination, a stationary cutting blade in the form of an unhardened unground flexible lamel of a maximum thickness of 0.0028 inches, serrated longitudinal edges on said stationary cutting blade, outwardly curved portions of the teeth of said serrated edges extending into the intervening tooth gaps to provide a larger exterior width for said gaps and an inner end of the gaps of a maximum width of 0.008 inches, a flexible steel lamel of similar shape as said stationary cutting blade, but with smooth longitudinal edges and of somewhat greater thickness and slightly smaller width so as to clear said teeth on said stationary blade, superimposed on said stationary cutting blade, a rigid hardened movable cutting blade situated underneath said stationary cutting blade, serrated longitudinal edges on said movable cutting blade, a carrier plate centrally arranged between said stationary and said movable cutting blade and extending longitudinally of said blades, a top plate of smaller width than said lamel and concaved in the transverse direction overlying said lamel, screw downs for said top plate for flexing said lamel and said stationary cutting blade with the aid of said carrier plate down on said movable cutting blade, for pressing the flexible teeth of said stationary cutting blade against the rigid teeth of said movable cutting blade, and means for actuating said movable cutting blade in the flexed condition of said stationary cutting blade.

7. In an electric shaving machine for dry shaving, in combination, a stationary cutting blade in the form of an unhardened unground flexible lamel of a maximum thickness of 0.0028 inches, serrated longitudinal edges on said stationary cutting blade, a flexible steel lamel of similar shape as said stationary cutting blade, but with smooth longitudinal edges and of somewhat

greater thickness and slightly smaller width so as to clear said teeth on said stationary blade, superimposed on said stationary cutting blade, a rigid hardened movable cutting blade situated underneath said stationary cutting blade, serrated longitudinal edges on said movable cutting blade, a carrier plate centrally arranged between said stationary and said movable cutting blade, and extending longitudinally of said blades, adjustable supporting sleeves for said carrier plate screwed in the body of the machine and adapted for varying the distance between said carrier plate and said movable cutting blade, a top plate of smaller width than said lamel and concaved in the transverse direction overlying said lamel, screw downs for said top plate passed through said supporting sleeves for flexing said lamel and said stationary cutting blade with the aid of said carrier plate down on said movable cutting blade, rectangular heads of said screw downs fitted into corresponding recesses in said top plate for preventing rotational displacement of the screw shafts, nuts provided on the shafts of said screw downs, an enlargement of said nuts locked to the machine body a screw threaded sleeve connected to said enlargement, a clamping sleeve arranged in the machine body for engaging said sleeve for securing the same on the screw shaft, and means for actuating said movable cutting blade in the flexed condition of said stationary cutting blade.

8. In an electric shaving machine for dry shaving, in combination, a stationary cutting blade in the form of an unhardened unground flexible lamel of a maximum thickness of 0.0028 inches, serrated longitudinal edges on said stationary cutting blade, a flexible steel lamel of similar shape as said stationary cutting blade, but with smooth longitudinal edges and of somewhat greater thickness and slightly smaller width so as to clear said teeth on said stationary blade, superimposed on said stationary cutting blade, a rigid hardened movable cutting blade situated underneath said stationary cutting blade, serrated longitudinal edges on said movable cutting blade, a carrier plate centrally arranged between said stationary and said movable cutting blade and extending longitudinally of said blades, a guard member for the skin arranged at each side of the machine body below the teeth of the cutting blades, tines of said guard members so arranged as to provide extrusion passages for cooling air, exterior projecting portions of said tines extending adjacent to the teeth of the cutting blades, a top plate of smaller width than said lamel and concaved in the transverse direction overlying said lamel, screw downs for said top plate for flexing said lamel and said stationary cutting blade with the aid of said carrier plate down on said movable cutting blade, a portion of the machine casing disposed rearwardly of the cutting blades to provide a hollow handle, a terminal cap arranged on the outer end of said handle and provided with air entrance openings, a stage ventilator accommodated in the hollow space of said handle, air communication means provided between said hollow space and said extrusion passages, and means for actuating said stage ventilator and said movable cutting blade in the flexed condition of said stationary cutting blade.

WALTER BRUNNER.
